UNITED STATES PATENT OFFICE.

JOSEPH BRAKELEY, OF FREEHOLD, NEW JERSEY.

CAN-HEADING MACHINE.

SPECIFICATION forming part of Letters Patent No. 307,908, dated November 11, 1884.

Application filed July 17, 1884. (No model.)

To all whom it may concern:

Be it known that I, JOSEPH BRAKELEY, a citizen of the United States, and a resident of Freehold, Monmouth county, New Jersey, 5 have invented certain Improvements in Can-Heading Machines, of which the following is a specification.

The object of my invention is to construct a simple and effective device for applying the 10 heads to the bodies of sheet-metal cans; and this object I attain in the manner hereinafter set forth, reference being had to the accompanying drawings, in which—

Figure 1, Sheet 1, is a front view of the machine; Fig. 2, a longitudinal section of the 15 same; Fig. 3, Sheet 2, an enlarged section of the head-clamping portion of the machine; Fig. 4, a plan view of the same; and Fig. 5, a sectional plan on the line 1 2, Fig. 3.

20 A is the base or table of the machine, to which is firmly bolted or otherwise secured an annular frame, B, and to lugs *a* on the latter are hung by pins *b* a series of arms, *d*, each pair of arms carrying a segment, *D*, of 25 which three are shown in the present instance, these three segments surrounding the frame B, and each segment being acted upon by a spring, *e*, contained in a radial socket, *f*, forming part of said frame B, the tendency of the 30 springs being to force outward or expand the segments *D*. The outer faces of the segments are inclined, and are acted upon by a ring, *F*, the latter being connected by rods *g* to a bar, *G*, beneath the table. This bar *G* carries a 35 bolt, *h*, the upper end of which passes through an opening in one arm of a bell-crank lever, *J*, hung to lugs *i* on the under side of the table, the other arm of the lever carrying an anti-friction roller, *k*, which is adapted to a 40 slot, *k'*, in a bar, *K*, this slot being partly straight and partly inclined, so that as the bar is reciprocated vertically a vibrating movement will be imparted to the lever *J*. A spring, *m*, is interposed between the end of 45 the lever *J* and the bar *G*, and as the lever is vibrated in the direction of the arrow, Fig. 2, a yielding downward pressure will be imparted to the bar and to the ring *F* carried thereby, the ring and bar being elevated on the reverse 50 movement of the lever by the action of the latter on the head of the bolt *h*. The bar *K*

is reciprocated by means of a treadle, *M*, hung to the legs of the table, and the upper end of the bar is connected to a slotted block, *N*, rods *n n'* on which are adapted to guides *p* 55 at the upper ends of the standard *P* on the table, the lower end of the guide-rod *n'* carrying the presser-plate *S*.

On each of the standards *P* are two projecting studs, *s*, which are so located as to form 60 four gages, two for the upper portion and two for the lower portion of the can-body, and the latter is thus properly centered in respect to the segment *D*, and is also held in a vertical position, so as to insure its being thrust 65 directly downward into the flanged head confined by the segments.

The operation of the machine is as follows: The parts being in the position shown in Fig. 2, the operator throws a flanged head onto 70 the top of the frame *D*, where it is supported partly by the frame and partly by the radial spring-sockets *f*. A can being held against the gage-studs *s*, the treadle is depressed, carrying with it the bar *K*, the first result of 75 this movement being the operation of the lever *J* and the depression of the bar *G* through the medium of the spring *m*. A yielding pressure is thus applied to the bar and to the ring *F*, and the latter, acting on the inclined 80 outer faces of the segments *D*, forces the same inward until they confine the flanged head, the segments being notched so as to overlap the flange. The movement of the bar *K* continues until the presser-plate *S* strikes the top 85 of the can-body and forces the same downward until its lower end enters the flanged head confined by the segments *D*, the inner faces of the latter being inclined, so as to impart to the lower end of the can-body any 90 amount of compression necessary to permit the latter to enter the flanged head of the can.

I claim as my invention—

1. The combination of the frame *B*, the hinged segments *D*, the springs *e*, the compressing-ring *F*, and means for depressing said ring, as set forth.

2. The combination of the hinged segments *D* with the frame *B*, having radial sockets *f*, and springs *e*, contained therein and acting on 100 the segments, as set forth.

3. The combination of the retaining-seg-

ments, the ring F, acting thereon, the bar G, connected to the ring, the lever J, the bolt *h*, the spring *m*, and means for vibrating the lever, as set forth.

5 4. The combination of the retaining-segments, the compressing-ring and its bar G, the lever J and its roller *k*, and the bar K, having a slot, *k'*, as set forth.

' In testimony whereof I have signed my name to this specification in the presence of two sub- 10 scribing witnesses.

JOSEPH BRAKELEY.
